(57) **CLAIM**

We claim the ornamental design for the timer blade, as shown and described.

DESCRIPTION

FIG. 1 is a perspective view of the timer blade;
FIG. 2 is another perspective view thereof;
FIG. 3 is a top view thereof;
FIG. 4 is a bottom view thereof;
FIG. 5 is a front view thereof;
FIG. 6 is a back view thereof;
FIG. 7 is a side view thereof; and,
FIG. 8 is a side view thereof showing the side opposite that shown in FIG. 7.

The broken line showing of portions of the timer blade is for purposes of illustrating unclaimed portions thereof.

The broken lines consisting of long and short lines together are boundary lines that represent boundaries of the claimed design and form no part thereof.
